ABSTRACT

A novel food station comprises a plurality of cubbies, each sized to enclose a food portion container (FPC). Each cubby includes a cubby door and a door actuation mechanism that can open and close the cubby door independently from that of other cubbies. A heating system that can controllably heat the FPC within at least a first cubby, and a cooling system can perform cooling within at least a second cubby. The food station includes an internal transport system with an end effector that temporarily couples to the FPC, and controllably moves the FPC in a common transport space within the food station. The food station includes a control system that controls the heating, the cubby doors, and the movement of the internal transport system. Each cubby door, when closed, closes off the corresponding cubby interior space sufficiently to enable independent temperature control within the cubby interior space.

AUTONOMOUS FOOD STATION

CROSS-REFERENCE TO RELATED
APPLICATIONS

This application claims priority under 35 USC § 120 as a continuation-in-part to U.S. patent application Ser. No. 17/971,548 filed 2022 Oct. 21, which claims priority as a continuation-in-part to U.S. patent application Ser. No. 17/892,048 filed 2022 Aug. 19 (issued as U.S. Pat. No. 11,605,260), which claims priority as a continuation-in-part to U.S. patent application Ser. No. 17/683,329 (issued as U.S. Pat. No. 11,462,072), which claims priority as a continuation-in-part to U.S. patent application Ser. No. 17/387,936, and thereby this application also claims priority to U.S. provisional patent application 63/066,904 filed 2020 Aug. 18, and to U.S. provisional patent application 63/105,056 filed 2020 Oct. 23. The foregoing claims to priority are not an incorporation by reference.

BACKGROUND

Food vending machines are typically stocked with a finite selection of consumable food items, each with an indication of its price. Customers can insert payment and select one of the stocked items for purchase and consumption at the stored temperature, but if heating of the food item is required the customer must do that himself subsequently and remotely. The customer does not directly affect the selection or timing of the food items that are stocked in contemporary food vending machines, but rather the stocking is done on a regular basis without customer input. In the case of a conventional food vending machine, the maximum number of food item choices available to the customer is limited by the size and architecture of the machine; the customer can choose only items that are regularly stocked and therefore physically present within the machine at the time of the customer's selection.

Lockers have been disclosed for temperature-controlled storage and provision of heated food items, but those require selective customer access to many external doors, i.e., an access-controlled external door for each stored and vended food item. Such a requirement can cause the customer-accessible area of the lockers to be excessively large for many venues. Moreover, the number of external locker doors is undesirably limited (and therefore the number of food choices is also undesirably limited) because of a practical height restriction: it is inconvenient and potentially unsafe for customers to reach overhead to retrieve hot foods. Hence, locker systems have an undesirably limited expandability and capacity in many locations because they are inherently only one row deep (for customer access) and practically limited to being not more than approximately 6 feet tall.

SUMMARY

The inventors of the current application recognized a need in the art for an improved food storing and selling system, or a portion thereof, that may in certain embodiments: (1) help consumers to remotely pre-order desired food items or meals from a large menu of hot or cold choices, the number of menu options not being limited by the capacity of a vending machine; (2) autonomously store, cool, heat, and provide each chosen food item independently at different scheduled times and temperatures; (3) store and sell a sufficient variety and quantity of cold or hot food items

2

without requiring an excessively large customer-accessible area; (4) relax the time constraints for preparing and delivering hot meals to consumers, for example enabling such meals to be prepared and delivered well before consumption rather than immediately before consumption; and/or (5) improve economies of scale for production and delivery of hot meals. Certain embodiments of the autonomous food station disclosed herein can help meet one or more of the foregoing needs.

BRIEF DESCRIPTION OF THE DRAWINGS

For the purposes of illustration, there is shown in the drawings exemplary embodiments, but the claims define their own bounds and are not limited to the specific embodiments disclosed or shown.

FIG. 1 is a flow chart of various example interactions or communications that an embodiment of a novel autonomous food station may have with a customer, food partner, and delivery partner.

FIG. 2 is a front view of an autonomous food station according to an example embodiment of the present invention.

FIG. 3 is a left perspective view of the autonomous food station of FIG. 2, with a left cubby access panel opened from the exterior.

FIG. 4 is a right perspective view of the autonomous food station of FIG. 2, with a right cubby access panel opened from the exterior.

FIG. 5 is a perspective view of an example internal transport system for movement of portion containers from the right sided cubbies of an autonomous food station, according to an embodiment of the present invention.

FIG. 6 is an exploded perspective view of a cubby of an autonomous food station according to an example embodiment of the present invention, and a food portion container that can be used with the autonomous food station, after opening the cubby from within the interior of the autonomous food station to remove the portion container carrier and portion container.

FIG. 7 is a cross-sectional view of the portion container of FIG. 6.

FIG. 8 is a perspective cross-sectional view of the cubby of FIG. 6, in a closed state with the portion container inside.

FIG. 9 is a top view of the interior of the cubby of FIG. 6, in a closed state with the portion container inside.

FIG. 10 is a perspective view of the portion container carrier of the cubby of FIG. 6.

FIG. 11 is an exploded view of an example heat transfer assembly for a cubby of an autonomous food station according to an example embodiment of the present invention.

FIG. 12 is a cross-sectional view of a cubby including a portion container of an autonomous food station according to an example embodiment of the present invention that utilizes the heat transfer assembly of FIG. 11.

FIG. 13 depicts an example of forced convection by a blower fan of the heat transfer assembly of the cubby of FIG. 12.

FIG. 14 is a cross-sectional view of a plurality of cubbies of an autonomous food station according to an example embodiment of the present invention, showing an example of how cooling and heating fluids may be circulated to the cubbies.

FIG. 15 is a schematic diagram of a system for cooling and heating fluids for independently heating or cooling food

portion containers in individual cubbies of an autonomous food station, according to an example embodiment of the present invention.

FIG. 16 is a side view of the interior of an autonomous food station that includes in a base compartment portions of the example cooling and heating system of FIG. 15.

FIG. 17 is a perspective view of the base compartment that supports the example autonomous food station of FIG. 16.

FIG. 18 depicts the base compartment of FIG. 17 viewed from an opposing direction.

FIG. 19 is a perspective view of the internal transport system of the autonomous food station of FIG. 5.

FIG. 20A through FIG. 20E is a series of perspective views showing examples of movement of a portion container by the internal transport system of FIG. 5, within an autonomous food station according to an example embodiment of the present invention.

FIG. 21 is a front perspective view of a front-loading autonomous food station according to another embodiment of the present invention.

FIG. 22 is a perspective view of the front-loading autonomous food station of FIG. 21 with two left cubby storage drawers drawn open for external access.

FIG. 23 depicts the interior of the front-loading autonomous food station of FIG. 21.

FIG. 24A is a cross-sectional view of a food portion container that may be used with an autonomous food station according to an example embodiment of the present invention.

FIG. 24B is an exploded perspective view of a cubby of an autonomous food station according to another example embodiment of the present invention, and the food portion container of FIG. 24A, after opening the cubby from within the interior of the autonomous food station to remove the portion container carrier and portion container.

FIG. 24C is a cross-sectional view of a cubby of an autonomous food station according to an example embodiment of the present invention, in a closed state with the food portion container of FIG. 24A inside.

FIG. 25 is a perspective cross-sectional view of a portion of the interior of an autonomous food station according to another example embodiment of the present invention, showing a plurality of cooled cubbies.

FIG. 26A depicts four cubbies of an autonomous food station according to an alternative embodiment of the present invention, all having actuatable doors in closed positions.

FIG. 26B depicts one of the cubbies of FIG. 26A, having its actuatable door in an open position.

FIG. 26C depicts an optional rack and pinion mechanism for door actuation of the cubby of FIG. 26B.

FIG. 26D is a perspective side view of two of the cubbies of FIG. 26A, except the lower cubby door is opening and clearing the cubby immediately above it because of an optionally tilted door actuation plane.

FIG. 27 is a perspective view of a food portion container grabber end effector of the internal transport system of an autonomous food station, according to an alternative embodiment of the present invention.

FIG. 28A depicts the grabber end effector of FIG. 27 separate from the rest of the internal transport system, as actuated to a grab position.

FIG. 28B depicts the grabber end effector of FIG. 27 separate from the rest of the internal transport system, as actuated to a release position.

FIG. 29A depicts the grabber end effector of FIG. 27 separate from the rest of the internal transport system and in a release position, and approaching a food portion container that is within an open cubby.

FIG. 29B depicts the grabber end effector of FIG. 27 separate from the rest of the internal transport system and grabbing a food portion container that is within an open cubby.

FIG. 29C depicts the grabber end effector of FIG. 27 separate from the rest of the internal transport system and removing a food portion container from an open cubby.

FIG. 30 is a perspective view of a forklift end effector of an internal transport system of an autonomous food station, according to an alternative embodiment of the present invention.

FIG. 31A depicts the forklift end effector of FIG. 30 separate from the rest of the internal transport system and approaching a food portion container that is within an open cubby.

FIG. 31B is another depiction of the approach shown in FIG. 31A, except with the cubby enclosure removed to better show that the internal transport system optionally moves the forklift end effector forward at a level that is below a radially protruding circumferential rim of the food portion container.

FIG. 31C depicts the forklift end effector of FIG. 30 separate from the rest of the internal transport system and removing a food portion container from an open cubby.

FIG. 32 is a perspective view of a key lift end effector of an internal transport system of an autonomous food station, according to an alternative embodiment of the present invention.

FIG. 33A depicts the key lift end effector of FIG. 32 separate from the rest of the internal transport system.

FIG. 33B depicts the key lift end effector of FIG. 32 separate from the rest of the internal transport system and approaching a food portion container that is within an open cubby.

FIG. 34A is a perspective view of a tray end effector approaching a food portion container in a cubby, according to an alternative embodiment of the present invention.

FIG. 34B is a perspective view of the tray end effector of FIG. 34A being lowered by the internal transport system to engage a hook with the food portion container.

FIG. 34C is a perspective view of the tray end effector of FIG. 34B after the food portion container is pulled on to the tray by actuating the hook.

FIG. 35 is a perspective view of a conveyor belt end effector of an internal transport system of an autonomous food station, according to an alternative embodiment of the present invention.

FIGS. 36A and 36B depict different perspective views of the conveyor belt end effector separate from the rest of the internal transport system.

FIG. 36C depicts an optional configuration for a mechanism to drive the conveyor belt of the end effector of FIG. 35.

FIG. 37A depicts a cubby of an autonomous food station according to an embodiment of the present invention that is compatible with an internal transport system having a conveyor belt end effector, shown with an actuatable cubby door in a closed position.

FIG. 37B depicts the cubby of FIG. 37A, except with its actuatable door in an open position.

FIG. 38A depicts the conveyor belt end effector of FIG. 36A approaching a food portion container inside the cubby of FIG. 37B.

FIG. 38B depicts the conveyor belt end effector in position beneath the food portion container of FIG. 38A.

FIG. 38C depicts the conveyor belt end effector retrieving the food portion container of FIG. 38A.

FIG. 39 is a perspective view of the conveyor belt end effector of FIG. 35, after retrieving a food portion container from one of the plurality of cubbies of an autonomous food station according to an embodiment of the present invention.

DETAILED DESCRIPTION OF EXEMPLARY EMBODIMENTS

FIG. 1 is a flow chart 100 of various example interactions or communications that an embodiment of a novel autonomous food station 102 may have with a customer 108, food partner 106 (e.g. food provider), and delivery partner 112. In the embodiment of FIG. 1, the customer 108 may interact with the food partner 106 or the autonomous food station 102 when ordering or paying for a consumable food item or meal, collecting the meal, or returning a portion container (P.C.) 110 after use. The delivery partner 112 may interact with the food partner 106 when picking up or returning portion containers 110, or interact with the autonomous food station 102 when loading them into or collecting them from the autonomous food station 102. The food partner 106 may interact with the autonomous food station 102, customer 108, or delivery partner 112, when providing or updating menus, receiving orders of or payment for customer or cumulative menu choices 109, 119, or coordinating delivery or retrieval of portions containers 110.

The autonomous food station 102 at a particular site 104 may be owned by the food partner 106. Alternatively, the owner or operator of the autonomous food station 102 may hire or otherwise contract with the food partner 106 to prepare and supply consumable meals or snacks. More than one food partner 106 may prepare and supply meals to any given autonomous food station 102, so that a customer 108 may have the option to purchase consumable snacks and meals of numerous types. The food partner 106 may be a well-known restaurant whose brand more readily attracts consumers, a commissary, etc. The owner may be a franchisee who operates one or more autonomous food stations for a franchiser who controls what consumable food items are offered and partially profits from their sale. The food partner might profit from the sale of meals to the franchisee and the franchisee may profit from the sale of meals to end customers 108 via the autonomous food station 102. The owner of the autonomous food station 102 may pay a location owner (e.g. the owner of the site 104) a rental fee or a share of the profits for being allowed to place the autonomous food station 102 in one or more convenient location(s) owned by the location owner.

Convenient locations for the autonomous food station 102 may include places frequented by consumers who are in the same vicinity day after day such as apartment building lobbies, office buildings, office lunchrooms, workplace lobbies, university cafeterias, hospital cafeterias, taverns, etc. Numerous autonomous food stations like the autonomous food station 102 may be conveniently positioned around a neighborhood, town, or city. The autonomous food station 102 could be installed in private or public locations, such as downtown business centers, ballparks, beaches, campgrounds, other recreational venues, or airport terminals or train stations where consumers could pick up a pre-ordered meal before boarding.

Either the food partner 106 or the owner of the autonomous food station 102 may offer the same menu for

extended periods or may periodically (e.g. weekly) generate a new menu with a range of meal choices (a steak dinner, soup and sandwich, burger and fries, snacks, etc.), or with a range of meal components (proteins, sides, vegetables, etc.), or a range of cuisine ethnicities (Italian, Chinese, Mexican, etc.), or with a range of desserts (hot apple pie, cold desserts, room temperature pastries, etc.). A customer 108 (e.g. the ultimate consumer) reviews and selects consumable food items from the menu(s) 111 offered by one or more food partners 106.

The autonomous food station 102 may include software and hardware for enabling consumers to order and pay for a desired food consumable (e.g. meal, snack, salad, dessert, etc.) from an extensive menu of hot or cold choices and from one or more food partners 106. For example, the autonomous food station 102 may include a system computer and food station control logic 115. The food station control logic 115 may be a control system having conventional micro-electronics, software and/or firmware, conventional volatile and/or non-volatile memory, and that is conventionally wired and programmed to be capable of controlling the electromechanical actuators and heating and cooling systems of the autonomous food station 102.

The customer 108 may select and order a customer menu choice 109 in a variety of ways. For example, an app may be downloaded to the customer's smartphone for registration or unregistered interaction with one or more autonomous foods stations 102 and/or an on-line site. The app may query the customer's location and then query, store, or update information about various autonomous food stations 102 in the customer's region, or available menus from which the customer 108 may choose food items. The app may allow the customer 108 to register and input relevant personal information, payment information, food type preferences, dietary restrictions and allergies, most common location of use ("home base"), etc. The registered customer 108 may be required to select an account password to verify the customer's identity to the app, and may be assigned a customer identification key 117 for verify the customer's identity to the autonomous food station 102.

In certain embodiments, the autonomous food station 102 may include a user interface allowing the customer 108 to input customer identification information (e.g. the customer identification key 117) to receive or place a food order at the site 104. In this way, for example, the customer 108 might conveniently place tomorrow's food order while picking-up today's meal. Accordingly, the user interface of the autonomous food station 102 might prompt the customer 108 such as "Would you like to place another order," or "10% off if you place another order within the next 15 minutes," etc., thereby promoting additional sales before the customer 108 has eaten (and so is presumably hungry). Alternately, the customer 108 may be able to order meals via a call-in phone number.

The customer 108 may communicate an order of customer menu choice 109 in advance of the desired time of receipt of the food consumable, for example the day before the desired day of receipt (Day 0). For example, as described above, the customer 108 may communicate the customer menu choice 109 via a call-in number, or remotely using a smartphone app or on-line site, or via a system program and user-interface on the autonomous food station 102. The customer's order may be stored in the autonomous food station control logic 115 and the customer may be provided with a customer identification key 117 (e.g. a security code) for customer identity verification at the autonomous food station 102. The software may allow customers to reschedule the

time of receipt in advance, for example prerequisite upon using the customer identification key 117 to verify that rescheduling is being done by the customer and not another person.

Cumulative customer menu choices 119 are preferably transmitted to the food partner 106 who then prepares and places each selected food consumable into a portion container 110. The autonomous food station 102 preferably allows delivery of the consumable from the food partner 106 at an earlier time, and then provides the consumable to the customer 108 in a ready-to-eat condition in the sealed portion container at or around the later time. Before the desired time of receipt, for example on the morning of Day 0, the portion containers 110 may be picked up from the food partner 106 by a delivery partner 112, and delivered to the autonomous food station 102, for example in a refrigerated vehicle 114. The autonomous food station 102 may enable loading of pre-ordered consumables from one or more providing food partners 106 into storage chambers (i.e. cubbies). In certain embodiments, the portion containers 110 may be randomly loaded into individual cubbies 116 of the autonomous food station 102.

The autonomous food station 102 preferably includes a heating and cooling system 230 to enable the customer 108 (e.g. a consumer) to collect the chosen food consumable in a fresh and heated or cooled state at a convenient location at a chosen future time. For example, the heating and cooling system 230 of the autonomous food station 102 includes equipment to preferably enable each cubby 116 to store a consumable at a refrigerated temperature that can maintain the freshness of that consumable until an appropriate time before receipt by the customer 108, and to then begin heating the consumable so that it will be ready to consume when received, for example by beginning to heat a food portion container in a cooled cubby at a scheduled time, or moving a food portion container from a cooled cubby to a heated cubby at a scheduled time.

Each portion container is preferably provided with a label 124 that can be read and its associated data stored in the memory of the food station control logic 115. For example, the associated data may be used by the control system of the food station control logic 115 to determine the temperatures and heating and cooling schedule and durations for the cubby 116 into which the portion container 110 is loaded. In that way, the labels 124 of each of the portion containers 110 loaded into the autonomous food station 102 may provide the information needed for the food station control logic 115 to properly control the temperature versus time for each of the cubbies 116, independently of the other cubbies 116. Alternatively, some of the information may be provided via conventional microelectronics that can communicate via an internet connection, for example via the internet from the food partner 106, or alternatively may be input directly at the site 104 by the delivery partner 112 via a user interface of the autonomous food station 102 itself.

In this way, the autonomous food station 102 may enable the food partner 106 to prepare and supply meals that are intended to be served warm or hot to the autonomous food station 102 well in advance of regular mealtimes or expected receipt by the customer 108, thereby relaxing the time constraints for preparing and delivering warm or hot meals to consumers, for example enabling such meals to be prepared and delivered well before consumption rather than immediately before consumption.

The autonomous food station 102 also preferably includes an internal transport system 164 for moving the portion container 110 corresponding to customer menu choice 109

to a collection hatch 113 of the autonomous food station 102 at the demand of the identified customer 108 at or around the scheduled time of receipt, and allows access to the collection hatch 113 by the customer 108 after verification of the customer identification key 117. In certain embodiments the collection hatch 113 may be located at a height determined to be most convenient for the average customer. Because internal transport of the portion containers 110 is accomplished by the internal transport system 164 to a conveniently located collection hatch 113, the autonomous food station 102 may store and sell a large variety and quantity of cold or hot food items without requiring an excessively large customer-accessible area and without requiring customers to access lockers that are too high or out of reach. For example, because of the internal transport system 164, the customer need not be provided direct access to everything that is stored but rather only the collection hatch 113.

The information on the label 124 of the portion container 110, for example cooling instructions for storage or heating instructions for preparation of the consumable food item therein, the identification (e.g. number) of the cubby 116 in which that portion container 110 is stored, and the customer identification key 117, may be scanned or otherwise conventionally input and stored in the food station control logic 115. After the label 124 of each portion container 110 has been scanned, the food station control logic 115 may command the system to refrigerate the cubbies 116 containing portion containers 110 to maintain a temperature suitable for extended safe storage of cooked food (e.g. 37° F.), for example to reduce any adverse effect upon the taste and flavor of the food while the consumable is stored.

If the portion container 110 holds a meal to be delivered warm or hot, then the food station control logic 115 may command heating of the food portion container in its corresponding cubby 116, or movement of the food portion container from a cooled cubby to a heated cubby, sufficiently in advance of the scheduled or amended time for pick-up by the customer 108 (e.g. one hour prior, or a period sufficient to achieve an appropriate food serving temperature such as 140° F.), and keep it at that temperature until receipt by the customer 108. If the food is to be served cold, it may be maintained at the refrigerated temperature. If the food is to be served at room temperature, it may be warmed only to room temperature.

Customers arriving at the site 104 of the autonomous food station 102 to pick up their food preferably will first identify themselves to the food station control logic 115 using their customer identification key 117. Recognizing the customer 108, the food station control logic 115 may then command the internal transport system 164 to internally convey the corresponding portion container 110 from its cubby 116 to the collection hatch 113. The food station control logic 115 preferably keeps track of which cubbies 116 no longer contain portion containers 110, and stops heating or cooling in those cubbies 116 for improved energy efficiency. The food station control logic 115 may also recognize when a customer has not collected her portion container 110 before the expiration of some period after the requested pick-up time, and may then send a reminder, such as by call or text to the customer's smartphone, by email, or via a smartphone app. Based on feedback which may then be provided by the customer 108, the food station control logic 115 may keep the food at its heated temperature for an additional specified and biologically safe period of time, chill the food to avoid spoilage and reheat if and while biologically safe, or chill the portion container 110 and prompt the food delivery partner 112 to remove the un-claimed portion container 110 during

the next delivery and retrieval visit to site 104 (e.g. for subsequent disposal of its contents and cleaning for reuse by the food partner 106).

After customers 108 have consumed their food, they may place the empty portion containers 110 into a storage unit 128, where they may be kept at a desired temperature and humidity (e.g. moist to facilitate future cleaning). The delivery partner 112 may later retrieve them (e.g. the following morning) from the storage unit 128, for example to return them to the food partner 106 to be washed and sterilized for re-use. The storage unit 128 may be a large container external of the autonomous food station 102 intended merely to collect the empty portion containers 110 in a sanitary manner apart from the autonomous food station 102. Alternatively, the storage unit 128 may be an internal portion and function of the autonomous food station 102. If internal, the storage unit 128 may have means to move, scan, and identify the returned portion container 110. Whether internal or external, the customer 108 may ultimately receive a return deposit or credit against his account once the returned portion container 110 is scanned and identified after return. If the portion containers 110 are disposable, compostable, or recyclable, the portion containers may be marked with disposal instructions or icons that guide the customer 108 accordingly.

FIG. 2 is a front view of an autonomous food station 102 according to an example embodiment of the present invention. FIG. 3 is a left perspective view of the autonomous food station 102, with a thermally insulated left cubby access panel 196L opened from the exterior. FIG. 4 is a right perspective view of the autonomous food station 102, with a thermally insulated right cubby access panel 196R opened from the exterior. FIG. 5 is a perspective view of an example internal transport system 164 for movement of portion containers 110 from the right sided cubbies 116 of the autonomous food station 102.

In certain embodiments, the autonomous food station 102 may have a rectangular cuboid shape, for example of sufficient width and height to enclose 72 cuboid cubbies 116 for storing food portion containers 110, while preferably (but not necessarily) fitting through a standard sized commercial doorway. For example, in a particular embodiment, such an autonomous food station 102 may be approximately 35" wide, 78" tall, and 49" deep. In certain embodiments the collection hatch 113 may be positioned approximately half-way up the height of the station to ensure convenient customer access thereto. Each of the left and right cubby access panels 196L and 196R is preferably large enough to provide visibility and external access to the cubbies 116 for loading and cleaning, and is preferably insulated to optionally serve as the outside wall of the cubbies 116.

A base compartment 197 forming the lower portion of the autonomous food station 102 may be dedicated to house the cooling and heating system and various controls. It may also house the system computer and control logic 115, and support the rest of the autonomous food station 102, including the internal transport system 164 and the cubbies 116. The walls 199 of the autonomous food station 102 may include thermal and acoustic insulation and be structural capable of carrying the weight of the rest of the autonomous food station 102. The walls 199 may optionally include left and right base compartment air vents 191, 193.

The delivery partner 112 may have a key or access code to externally open the left and right cubby access panels 196L and 196R to load food items or collect unused food items. As will be described subsequently herein, the autonomous food station 102 may include an identification site 122

with a scanner 171 to read a label 124 or code on each portion container 110, so that the food station control logic 115 can automatically associate each portion container 110 with its corresponding cubby 116 (i.e. internal location). In 5 embodiments where the autonomous food station 102 is so equipped, the delivery partner 112 may load each new portion container 110 (one per cubby 116) randomly, without concern for specific positions or following a specific order. After all portion containers 110 are loaded into their cubbies 116, the internal transport system 164 may be used to 10 transport each portion container 110 to the identification site 122 to have its label 124 scanned, and then be returned to its cubby 116. The food station control logic 115 preferably associates in its memory the identified meal with the associated customer identification key 117 and its corresponding cubby 116—now a known location for that meal. Each meal 15 may have a meal preparation instruction specific thereto. This instruction also may be stored in the memory of the food station control logic 115, or may be provided to the logic by a code on the label 124. For example, a soup may 20 be best served at 160° F. while a grilled cheese sandwich may be best served at 130° F., and a tuna sandwich may be best served at room temperature. Such serving temperature preparation instructions may be associated with the corresponding cubby 116 by the food station control logic 115.

FIG. 6 is an exploded perspective view of a cubby 116 and portion container 110 of an autonomous food station according to an example embodiment of the present invention, after opening the cubby 116 from within the interior of the 30 autonomous food station to remove a portion container carrier 174 and portion container 110. As shown in FIG. 6, the portion container 110 may include a label 124, for example which includes scannable information specific to that portion container 110, the meal inside, and/or the 35 associated customer. FIG. 7 is a cross-sectional view of the portion container 110 of FIG. 6. When separated, the lid 151 of the portion container 110 may be stackable with lids of other like portion containers, and the base 153 of the portion container 110 may be stackable with the bases of other like 40 portion containers for compact nested storage or transport.

FIG. 8 is a perspective cross-sectional view of the cubby 116 of FIG. 6, in a closed state with the portion container 110 inside. FIG. 9 is a top view of the interior of the cubby 116 of FIG. 6, in a closed state with the portion container 110 inside. FIG. 10 is a perspective view of the portion container carrier 174 of the cubby 116 of FIG. 6. In certain embodiments, the portion container 110 may have a rounded shape which, being similar to most dishware, may be familiar to customers as a food serving container. In certain embodiments, air circulation may be improved for heating and cooling the portion container 110 within the cubby 116 because cubby 116 has a cuboid inner chamber, while the portion container 110 has a rounded shape that leaves peripheral space for the air flow.

The cubby 116 is preferably thermally insulated to save 55 energy and facilitate establishment and maintenance of a temperature difference between the cubby's interior and a common transport space within the autonomous food station 102, as directed by the food station control logic 115. As 60 shown in FIG. 8, the cubby 116 may include enough internal space for the portion container 110, a heat transfer assembly 130, and insulation on all sides. In certain embodiments, the back 155 of the cubby 116 may be formed by a portion or region of one of the insulated left and right cubby access panels 196L and 196R. In the embodiment of FIG. 10, the portion container carrier 174 includes two basic elements: a portion container support plate 159, and a carrier plate 163.

The carrier plate 163 includes a front panel 157 (of the cubby 116) to which the portion container support plate 159 may be permanently fixed. The front panel 157 of the cubby 116 may include insulation of adequate thickness to improve the efficiency of heating or cooling inside the inside of the cubby 116 (e.g. approximately 1" thickness in certain embodiments). Cubbies that are intended to together heat or cool food portion containers as a group may forego insulation on separating walls between them. The portion container support plate 159 is preferably designed to support the portion container 110 within the cubby 116, and thereby may improve heated or cooled air circulation around the portion container 110. For example, the portion container support plate 159 may comprise a horseshoe-shaped horizontal metal plate that fits around a circular rim that protrudes downwardly from the base 153 of the portion container 110.

The carrier plate 163 of the portion container carrier 174 may include a handle 165 that can be grasped by an end-effector 172 of the internal transport system 164 of FIG. 5. In the embodiment of FIG. 10 the portion container carrier 174 serves to carry the portion container 110, for example as it is transported by the internal transport system 164 of FIG. 5 (e.g. from the cubby 116 to the collection hatch 113 to be collected by the customer 108, or to the identification site 122 for scanning of the label 124 of the portion container 110). The portion container support plate 159 preferably can slide out from around a lower rim that protrudes downwardly from the base 153 of the portion container 110, so that the portion container 110 may be remain in the collection hatch 113 while the portion container carrier 174 is being withdrawn by the internal transport system 164. In this way, the portion container carrier 174 may facilitate loading and removal of the portion containers from cubbies 116 and the collection hatch 113.

FIG. 11 is an exploded view of an example heat transfer assembly 130 for use in a cubby 116 of an autonomous food station according to an example embodiment of the present invention. In the embodiment of FIG. 11, the heat transfer assembly 130 optionally includes a housing 267, a blower fan 158, a heating and cooling element 167, and a temperature sensor 162 (e.g. a negative temperature coefficient thermistor). FIG. 12 is a cross-sectional view of a cubby 116 including a portion container 110 of an autonomous food station according to an example embodiment of the present invention, which utilizes the heat transfer assembly 130 of FIG. 11. FIG. 13 depicts an example of forced convection by a blower fan 158 of the heat transfer assembly 130 of the cubby 116 of FIG. 12, with arrows depicting a simplified representation of a resulting air flow.

FIG. 14 is a cross-sectional view of a plurality of cubbies 116 of an autonomous food station according to an example embodiment of the present invention, showing an example of how cooling and heating fluids may be circulated to the cubbies 116. FIG. 15 is a schematic diagram of a hydronic heating and cooling system 230 for heating, cooling, and circulating thermal fluid(s) for individually and independently heating and cooling food portion containers in the cubbies 116 of an autonomous food station according to an example embodiment of the present invention. FIG. 16 is a side view of the interior of an autonomous food station 102 that includes a base compartment 197 that houses portions of the example cooling and heating system of FIG. 15. The base compartment 197 may also include a housing 198 for the system computer and control logic 115. FIG. 17 is a perspective view of the base compartment 197 that supports

the example autonomous food station 102 of FIG. 16. FIG. 18 depicts the base compartment 197 of FIG. 17 viewed from an opposing direction.

In the embodiment of FIGS. 14-16, each portion container 110 stored within a corresponding insulated cubby 116 may be individually cooled and heated independently of the other portion containers 110 inside the other cubbies 116, for example to maintain a temperature difference between individual cubbies, or between one or more cubbies and the 10 common transport space where food portion containers are moved within the autonomous food station. In certain embodiments, the independent heating and cooling may be done by a hydronic system as shown, but in other embodiments another conventional heating or cooling technology 15 may be used, such as a separately switched electrical heating element in each insulated cubby 116, or by provision of a microwave magnetron for directing microwave radiation to controllably heat an enclosed food portion container in one or more shielded cubbies, etc.

20 In certain embodiments, one or more fluids may be heated, cooled, and distributed for circulation through the heat transfer assemblies 130 of the cubbies 116 by a hydronic system like the example heating and cooling system 230 shown in the schematic representation of FIG. 25. The hydronic heating and cooling system 230 may include a conventional refrigeration subsystem 132 (e.g. in certain embodiments a conventional 4000 BTU refrigeration subsystem may be sufficient), for example, having a compressor 133, a shell and tube evaporator 134, a condenser 30 135, and a high-to-low pressure valve 137, for cooling a thermal fluid 136 (e.g. a liquid used for heat transfer, such as water or a solution or fluid having a lower freezing temperature than does water).

The hydronic heating and cooling system 230 may also 35 include a conventional boiler 138 with a submersed electric heating element 142. In this context the term "boiler" does not imply that the thermal fluid is necessarily brought to its boiling point, and in certain preferred embodiments it is not boiled but rather heated to a temperature below its boiling 40 point. Rather, the term "boiler" is used here only to refer to a conventional apparatus for heating a liquid. Hence the heating and cooling system 230 may be a combination of two systems, a heating system that selectively provides heat to food portion containers in each of the cubbies 116 45 independently of the other cubbies 116 (e.g., with a heating rate and for a heating duration that is independently controlled by the food station control logic 115), and a cooling system that selectively removes heat from food portion containers in each of the cubbies 116 independently of the other cubbies 116 (e.g., with a cooling rate and for a cooling duration that is independently controlled by the food station control logic 115).

In the embodiment of FIG. 15, the hydronic heating and 50 cooling system 230 may include a hot return header or manifold 143, a hot supply manifold 144, a cold supply manifold 145, and a cold return manifold 147. These manifolds or headers may be connected to a series of circulation tubes 146, valves 148 (e.g. four-way port pinch valves that may be actuated by solenoids controlled by the food station 55 control logic 115), and conventional electrical pumps 150 for driving the thermal fluids through the heat transfer assemblies 130 of the cubbies 116. The food station control logic 115 preferably controls the operation of the pumps 150 and the valves 148. The valves and pumps may direct certain cubbies to commence or discontinue heating and others to commence or discontinue cooling at different times, and some cubbies may be capable of only heating or cooling by 60 65

omitting one or more of the circulation tubes 146 to such cubbies to simplify the system and reduce its total cost and complexity. While FIG. 15 shows a plurality of individually controllable pumps 150, such pumps optionally may be replaced by a single pump and one or more additional valves, functioning to supply heated or chilled thermal fluid independently to the heat transfer assemblies 130 under direction of the food station logic 115.

The circulation tubes 146 may be flexible insulated tubes, and may be channeled through a gap 154 between the cubbies 116. For example, in one example embodiment, the circulation tubes 146 optionally may be 12 mm diameter flexible tubes that are routed through 25 mm gaps 154. In certain embodiments, conventional insulated electric wires may be routed along with the circulation tubes 146 and be used to supply electrical power to the cubby blower fans 158 and the temperature sensors 162 of the heat transfer assemblies 130. In certain embodiments, the assembly of the autonomous food station 102 may include routing the circulation tubes 146 and electric wires into the gaps between the cubbies 116, connecting their ends as needed, and then filling the gaps with expandable polyurethane insulation after the tubes circulation 146 and electric wires have been tested and found to operate satisfactorily.

FIG. 19 is a perspective view of the internal transport system 164 of the autonomous food station 102 of FIG. 5. FIG. 20A through FIG. 20E is a series of perspective views showing examples of movement of a portion container 110 by the internal transport system 164. In the embodiment of FIGS. 19 and 20A, the internal transport system 164 can translate the end effector 172 in three orthogonal directions, e.g. along an X axis, Y axis, and Z axis 184 of a Cartesian coordinate system, to transport the portion containers 110 within a common transport space within the autonomous food station 102 under the control of the food station control logic 115. For example, the X axis may be horizontal and run side-to-side relative to the autonomous food station 102, the Y axis may be vertical, and the Z axis 184 may be horizontal and run front-to-back relative to the autonomous food station 102. The internal transport system 164 may include a support-frame 176 and conventional power and control cables. The internal transport system 164 may comprise conventional servo-controlled hydraulic or electromechanical actuators, such as orthogonal drive spindles 166 (e.g. lead screws) and drive motors 168 (e.g. stepper motors indexed by the control system of the food station control logic 115) as shown in FIG. 19, or may comprise another conventional mechanism for driving motion in the X-Y plane.

The internal transport system 164 preferably also includes an end effector 172 that may be adapted to temporarily couple to the handle 165 of the portion container carrier 174 of each cubby 116 (e.g. by latching on to the handle 165), to enable the internal transport system 164 to retract and transport portion container carriers 174 along with the portion container 110 that each supports. In certain embodiments the internal transport system may comprise a conventional robotic arm in a common transport space within the autonomous food station, with the end effector 172 attached to a distal end of the robotic arm.

The end effector 172 may be mounted on a motor-driven belt 182 (e.g. driven by a stepper motor under the control of the food station control logic 115) for movement along the Z axis 184, or alternatively may be driven along the Z axis 184 by another conventional servo-controlled hydraulic or electromechanical actuator, for example in the same manner as for the X axis or Y axis (e.g. by use of a Z-oriented lead

screw that is turned by a controlled stepper motor). The end effector 172 may include a plurality of brackets 186 (e.g., two L-shaped or T-shaped brackets), for example, one on the left and one on the right, for selectively coupling with (e.g. grabbing) the portion container carriers 174 on the left and right sides of the handle 165, respectively. Alternately the end effector 172 may include a single bracket that may swivel to the left or the right for coupling with the handle 165 of the portion container carrier 174.

In certain embodiments, one of the roles of the internal transport system 164 may be to move portion containers 110 within the common transport space within the autonomous food station, to and from an identification site 122 so that the content and location of each can become known to the food station control logic 115. This role is depicted by the series of perspective views shown in FIGS. 20A, 20B, and 20C. For example, after the portion containers 110 are loaded into the cubbies 116 (e.g. randomly by the delivery partner 112), the food station control logic 115 may command the internal transport system 164 to initiate identification of each portion container 110 by moving each portion container 110 to the identification site 122 for scanning of its label 124, and then returning it to its corresponding cubby 116. In certain embodiments, each cubby 116 may optionally include a conventional sensor (e.g. capacitive or magnetic sensor or pressure-sensitive switch) to signal to the food station control logic 115 whether the cubby 116 is empty or contains a portion container 110, so that the food station control logic 115 can efficiently avoid commanding the internal transport system 164 to transport portion container carriers 174 that do not support any portion container 110.

For cubbies 116 that include a portion container 110, the internal transport system 164 may methodically pick up one portion container 110 after another, and transport each to the identification site 122 so that its label 124 may be read by a scanner 171 (e.g. a camera, or QR code or barcode reader). The portion container's label information may then be associated with its location (i.e. corresponding cubby 116) by the food station control logic 115. The internal transport system 164 may then return the portion container 110 to its cubby 116 before repeating the process with the next portion container 110.

In certain alternative embodiments, the autonomous food station 102 may not need to use the internal transport system 164 for identification of the portion containers 110, or for associating each with its corresponding cubby 116 in which it is located. For example, use of the internal transport system 164 may not be necessary for identification and location of the portion containers 110 in embodiments in which the user interface of the autonomous food station 102 permits the delivery partner 112 to enter a portion container identification number for each cubby 116 that is loaded. Also, for example, use of the internal transport system 164 may not be necessary for identification and location of the portion containers 110 in alternative embodiments that include a label scanner in each cubby 116.

Another role of the internal transport system 164 may be to move portion containers 110 between cooled and heated cubbies at specified times, or to the collection hatch 113 for collection by the customer 108 at a specified time. This latter role is depicted by the series of perspective views shown in FIGS. 20A, 20B, 20D, and 20E. For example, when a customer 108 identifies herself to the user interface of the autonomous food station 102 for food collection, the food station control logic 115 may then command the internal transport system 164 to retrieve the corresponding portion

container 110 and transport it through the common transport space within the autonomous food station to the collection hatch 113.

The collection hatch 113 may include two shutters, a front external shutter 192 facing the customer and a rear internal shutter 194 at the back of the collection hatch 113 facing the interior space of the autonomous food station 102 and its internal transport system 164. The food station control logic 115 may be programmed to open and close these shutters during the internal transport of the portion container 110 into the collection hatch 113. For example the external shutter 192 may be servo controlled by an actuator such as a solenoid, so that the external accessibility of the collection hatch 113 is selective and controllable by the control system of the food station control logic 115. The internal shutter 194 may also be servo controlled by a conventional actuator such as a solenoid so that access from the collection hatch 113 to an interior of the autonomous food station 102 may be selectively denied while the external shutter 192 is open.

After the portion container carrier 174 is retracted from under the portion container 110 within the collection hatch 113, the internal transport system 164 preferably returns the portion container carrier 174 to its cubby 116, and then waits for the next command from the food station control logic 115.

Another optional role of the internal transport system 164 may be, in certain embodiments, to transport used portion containers 110 that are returned to the collection hatch 113 by customers 108 to an internal storage area of the autonomous food station 102. For example, when a customer 108 comes back after eating, or when a customer 108 comes to collect their next meal, certain embodiments may allow the customer 108 to insert a used and possibly empty or mostly-empty portion container back to the collection hatch 113. In certain preferred embodiments that may not be allowed, but rather an external storage for returned portion containers 110 may be utilized instead, for example, to avoid the risk that the autonomous food station 102 (e.g. the collection hatch 113) could become contaminated by handling used portion containers 110. Such risk may depend, in part, on the type of foods being sold.

In embodiments allowing internal return of used portion containers 110, the food station control logic 115 may respond to a “return container” prompt (e.g., from the customer 108 at the user interface of the autonomous food station 102) by causing the external shutter 192 of the collection hatch 113 to open to allow the customer 108 to place the used portion container 110 into the collection hatch 113. This may require no customer identity verification. The food station control logic 115 may then command the external shutter 192 to close and the internal shutter 194 to open so that the internal transport system 164 can move the used portion container 110 to an internal storage area directly, or first to the identification site 122 to identify the returned portion container 110 for credit to the customer 108. The food station control logic 115 may then prompt the customer 108 to give feedback about perceived meal quality, which may be used to adjust future menus 111 in general or future offerings to the particular prompted customer 108.

Another optional role of the internal transport system 164 may be, in certain embodiments, to transport a portion container 110 from a typical cubby 116, through the common transport space within the autonomous food station, to another cubby that can perform special or additional functions relative to typical cubbies 116. For example, based on information read from the label 124 of the portion container 110, the food station control logic 115 may determine that

the portion container 110 should be relocated to another cubby that has special or additional food preparation utilities. Examples of special or additional food preparation utilities may include shielding and a conventional microwave magnetron for rapid heating of a food portion container within a cubby, or a means for meeting a food moisture requirement such as conventional humidity control using a desiccant.

FIG. 21 is a front perspective view of a front-loading autonomous food station 200 according to another embodiment of the present invention. FIG. 22 is a perspective view of the front-loading autonomous food station 200 with two left cubby storage drawers drawn open for external access. FIG. 23 depicts the interior of the front-loading autonomous food station 200.

The front-loading autonomous food station 200 of the embodiment of FIGS. 21-23 optionally includes groups 202L, 202C and 202R of cubbies 216, each group accessed via its own internal transport system and collection hatch 213L, 213C, and 213R, respectively. Therefore, the front-loading autonomous food station 200 may have the capacity to serve a larger number of customers than the side-loading embodiment of FIGS. 2-4, which has only one internal transport system 164. As shown in FIG. 23, each of the 25 internal transport systems serving the groups 202L, 202C and 202R of cubbies 216 operates within its own common transport space, so that there are three common transport spaces within the front-loading autonomous food station 200.

Each group 202L, 202C and 202R of cubbies 216 may have its own food station control logic, or may share a common food station control logic. The food station control logic may direct the customer to collect food at a specific one of the collection hatches 213L, 213C, and 213R, according to which group 202L, 202C and 202R of cubbies 216 includes the customer's portion container 210. The delivery partner may service or load the entire station from the front of the autonomous food station 200, which may enable the autonomous food station 200 to be used in locations where the other sides of the autonomous food station 200 would be inaccessible, and may improve loading and cleaning efficiency.

The autonomous food station 200 may be further expanded to include additional groups of cubbies and additional internal transport systems arranged in side-by-side fashion. The increased capacity may allow the food partner 106 to provide additional un-ordered meals, snacks, desserts, side dishes, etc., to be loaded into the autonomous food station 200 for spontaneous purchasers, e.g., who find themselves hungrier than originally expected. The food station control logic of the autonomous food station 200 may prompt the customer to add to their pre-ordered purchase, for example with messages like “Would you like fries with that?,” or “Would you like to add a dessert?” Such items not pre-ordered may carry a premium cost, due to the risk the food partner 106 may take that the food items spoil before sale, and/or to encourage customers 108 to order in advance.

FIG. 24A is a cross-sectional view of a food portion container 510 that may include a lid 551 and may be used with an autonomous food station according to an example embodiment of the present invention. In this alternative embodiment, a base 553 of the food portion container 510 may comprise a ceramic material and include mating electrically conductive contact features 542, 544 (e.g. that extend or protrude downwardly) to accept electrical power, with a conventional electrically resistive heating element 546 of the type used in conventional hot plates connected in

series between the mating electrically conductive contact features. In this way, the bottom of the food portion container may function as a hot plate when enclosed within a cubby that can provide an electrical potential across the mating electrically conductive contact features 542, 544 of the food portion container 510.

FIG. 24B is an exploded perspective view of a cubby 516 of an autonomous food station according to another example embodiment of the present invention, and the food portion container 510 of FIG. 24A, after opening the cubby 516 from within the interior of the autonomous food station to remove the portion container carrier 174 and portion container 510. Referring now additionally to FIG. 24B, the portion container carrier 174 includes a carrier plate 163 with front panel 157 and a handle 165, and a portion container support plate 159. In this alternative embodiment, the portion container support plate supports the entire weight of the food portion container 510 when the portion container carrier 174 and food portion container 510 are removed from within the cubby 516.

In the example embodiment of FIG. 24B, the floor of the cubby 516 may include first and second electrically conductive features 582, 584, which can make electrical contact with mating features 542, 544 on the base 553 of the food portion container 510 (when enclosed in the cubby 516), respectively. After establishment of the foregoing electrical contacts, the heating system of the autonomous food station may selectively provide an electrical potential between the first and second electrically conductive features 582, 584 to power a conventional electrically resistive heating element 546 embedded in the food portion container 510. Alternative geometric arrangements of the electrically conductive features are possible and practical and contemplated by this disclosure, so long as the electrical contacts are established when the food portion container 510 is inserted into the cubby 516 (e.g., conventional spring-loaded conductive pins contacting the bottom or sides of the food portion container 510).

FIG. 24C is a cross-sectional view of the cubby 516, in a closed state with the food portion container 510 of FIG. 24A inside. Referring now additionally to FIG. 24C, the floor of the cubby 516 may include two electrically conductive features 582, 584, which can make electrical contact with mating features 542, 544 on the base 553 of the food portion container 510 (when enclosed in the cubby 516), e.g. to power an electrically resistive heating element 546 embedded in the food portion container 510. The heating system of the autonomous food station may selectively drive an electrical current via the first and second electrically conductive features 582, 584 through the resistive heating element 546 of the food portion container 510.

In the embodiment of FIG. 24C, the base 553 of the food portion container 510 may extend slightly below the portion container support plate 159 so that, when the portion container carrier 174 is inserted into the cubby 516, the mating electrically conductive features 542, 544 of the base 553 of the food portion container 510 will contact and rest upon the first and second electrically conductive features 582, 584 of the floor of the cubby 516, and the electrical contacts therebetween may then be maintained by gravity. The electrical contacts may be alternatively made and maintained by spring loaded pins, or other conventional means.

Alternatively, the electrically conductive contacts of cubby 516 may be eliminated entirely and replaced by a conventional electrically conductive coil, e.g., disposed in an insulative material of the floor of the cubby 516. For example, the insulative material may comprise a conven-

tional insulative ceramic material. In that alternative embodiment, the heating system may selectively drive an oscillating electrical current through the conventional electrically conductive coil of the cubby, to induce an electric current through a conventional resistive heating element comprised by the food portion container. The electrical circuit of the food portion container that includes the conventional resistive heating element may also include a capacitor to tune its resonant frequency for improved inductive coupling. Such heating of conventional hot plates or kettles by electrical power transferred via inductive coupling is well known in the art, for example as disclosed in U.S. Pat. No. 4,996,405 to Poumey, et al. The food portion container that is enclosed in the selected cubby herein may thusly be selectively heated by inductive coupling in an alternative embodiment of the heating system of the autonomous food station.

FIG. 25 is a perspective cross-sectional view of the interior of an autonomous food station 400 according to another example embodiment of the present invention. The food station 400 includes a frame 476 supporting an array of cubbies including a subarray of group-cooled cubbies 402. In the example embodiment of FIG. 25, a heating system of the autonomous food station 400 may—but does not necessarily—perform heating in any or all of the depicted subarray of cooled cubbies 402. As used herein, a “cooled cubby” is a cubby that the cooling system can cool, but it does not need to have a below-ambient temperature and the system does not have to be removing heat from it at the time that it is considered and identified herein as a “cooled cubby.” In a preferred embodiment, cooling of the subarray of cooled cubbies 402 is independent of any heating or cooling in any or all cubbies that reside outside the subarray of group-cooled cubbies 402.

The cooling system of the autonomous food station 400 preferably includes a blower and a thermally insulated air duct 445, 446, which can convey chilled air between an evaporator of a conventional air refrigeration system (e.g. disposed in base compartment 197 of FIG. 18) and the subarray of group-cooled cubbies 402. In the example embodiment of FIG. 25, the thermally insulated air duct 445, 446 is optionally a dual coaxial air duct with air flow towards the subarray of group-cooled cubbies 402 within an inner duct portion 445, and return air flow back to the evaporator within an outer duct portion 446. Such a coaxial arrangement may enhance space efficiency and reduce the quantity of needed thermal insulation. One or more of the group-cooled cubbies 402 optionally may also include a desiccant or other conventional means for decreasing the relative humidity of the air within that cubby.

Preferably an internal transport system 464 of the autonomous food station 400 can move a portion container carrier of a selected one of cooled cubbies 402 (e.g. cubby 416) through the common transport space of the autonomous food station to a selected heating cubby to heat a food portion container according to a heating schedule, or directly to the collection hatch 113 if the food is intended to be served unheated.

In certain alternative embodiments of the present invention, it may be desired for design simplicity, to reduce the number of components, to maintain cubby temperature differences more efficiently, or to reduce cost, for the internal transport system to be able to move food portion containers (FPCs) without the need for a plurality of FPC carriers. For example, it may be desirable for the end effector of the internal transport system of the autonomous food system to be able to retrieve an FPC from within a cubby without

taking a removable FPC carrier that includes the cubby's front panel along with it. (e.g. as otherwise would be done with the FPC carrier 174 of FIGS. 6 and 10).

In such alternative embodiments, the front panel of each cubby would remain with that cubby as its access door, rather than being temporarily being transported with the FPC (within the autonomous food station) away from the cubby. In such alternative embodiments, the end effector of the internal transport system would include a means to couple with and carry the FPC through the common transport space of the autonomous food station, which means may be considered as a single FPC carrier (comprising the end effector of the internal transport system) and that would not include the cubby front panel.

FIG. 26A depicts four cubbies 616, 617, 618, 619 of an autonomous food station according to an example alternative embodiment of the present invention. In the embodiment of FIG. 26A, each cubby has a front panel door 657 that stays with that corresponding cubby, and which can be automatically opened or closed by an example door actuation mechanism 650. In the view of FIG. 26A, all of the cubby front panel doors 657 are shown in the closed position. FIG. 26B depicts cubby 616 with its front panel door 657 moved by the door actuation mechanism 650 into an open position. FIG. 26C depicts the door actuation mechanism 650 according to an example embodiment, optionally including a rack 652 and pinion gear 651. However, it is contemplated that other conventional actuation mechanisms may be instead utilized or adapted to move the cubby front panel door 657 to its open and closed positions. It is also contemplated that a cubby front panel door may be attached and moved in other conventional ways (e.g., a hinged swinging door that opens and closes by action of a rotational actuator, and/or that is preloaded in a rest position by action of a spring).

FIG. 26D is a perspective side view of the cubbies 616 and 617 of FIG. 26A, showing that the door actuation plane of door 657 may be tilted from a truly vertical axis sufficiently so that when the door 657 is opening (as shown) it clears rather than interferes with the cubby 617 immediately above it. Such tilting would not be necessary for hinged swinging doors. One of ordinary skill in the art would realize from this description and from FIG. 26D that if the door 657 were designed instead to slide open sideways (rather than upwards) in another alternative embodiment, then the door 657 may need to be tilted instead from a truly horizontal axis to clear the cubby next to it (rather than above it), e.g., to clear cubby 619 of FIG. 26A. Alternatively, adjacent cubbies may be staggered sufficiently forward or backwards relative to each other (e.g., by at least the thickness of the sliding door 657) to avoid door opening interference, in which case the door actuation planes would not need to be canted.

FIG. 27 is a perspective view of a FPC grabber end effector 772 of the internal transport system 764 of an autonomous food station 700, disposed in the common transport space in front of a cubby 716 and a plurality of similar cubbies, according to an alternative example embodiment of the present invention. FIG. 28A depicts the grabber end effector 772 (separate from the rest of the internal transport system, for simplicity) with its grabber arms 774, 776 actuated to a grab position, i.e., a position in which the grabber arms 774, 776 would partially envelop (between the grabber arms 774, 776), and radially clamp to couple to, an outer surface of the FPC. In certain embodiments, the actuation of the grabber arms 774, 776 optionally may be accomplished by an actuator comprising a sliding hinged linkage 778 translated by a lead screw that is driven

by a stepper motor 779. FIG. 28B depicts the same grabber end effector 772 with its grabber arms 774, 776 actuated to a release position, i.e., a position in which the grabber arms 774, 776 would release an FPC.

FIG. 29A depicts the example grabber end effector 772 of FIG. 27 (separate from the rest of the internal transport system, for simplicity) in its release position, approaching an FPC 710 that is within a cubby 716. In the embodiment of FIG. 29A, the cubby 716 includes a door 757 that is actuated to its open position by an actuator that is optionally inside the cubby (e.g., a motor-driven pinion gear that engages with a rack on the inner face of door 757 rather than the outer face of door 757). FIG. 29B depicts the grabber end effector 772 grabbing the FPC 710 that is within the open cubby 716. FIG. 29C depicts the grabber end effector 772 removing the FPC 710 from the open cubby 716.

FIG. 30 is a perspective view of a forklift end effector 372 of an internal transport system 364 of an autonomous food station 300, holding an FPC 310 in the common transport space in front of a cubby 616 and a plurality of similar cubbies, according to an alternative embodiment of the present invention. FIG. 31A depicts the forklift end effector 372 (separate from the rest of the internal transport system, for simplicity) with its projecting fork arms 374, 376 approaching the FPC 310 that is within the cubby 616. As shown in FIG. 31A, the door actuation mechanism 650 has moved the front panel door 657 of the cubby 616 to the open position to allow the forklift end effector to access the FPC 310.

In the embodiment of FIGS. 30 and 31A, the cubby door 657, when closed, closes off the interior space within the cubby 616 on all sides, enabling the control system of the autonomous food station 300 to control a temperature within the interior space of the cubby 616 to be substantially different (e.g., $\geq 30^\circ$ F. different) from that of the common transport space within the autonomous food station 300. For example, the control and heating systems of the autonomous food station 300 may raise a temperature within the interior space of the cubby 616, including that within a FPC inside the interior space of the cubby 616, to an elevated serving temperature of 140° F. Alternatively, the control and cooling systems of the autonomous food station 300 may cool the interior space of the cubby 616 to a safe storage temperature of 37° F. Either of the two foregoing examples of temperatures within the interior space of the cubby 616 are considered herein to be substantially different from the typical temperatures expected in the common transport space within the autonomous food station 300 because the common transport space is not insulated in the embodiment of FIG. 30, and the autonomous food station 300 is typically situated in a room-temperature environment.

FIG. 31B is another depiction of the approach shown in FIG. 31A, except with the cubby enclosure removed to better show that the internal transport system (not shown) preferably moves the forklift end effector 372 forward, in this embodiment, at a level such that the fork arms 374, 376 will partially envelop, between the two fork arms 374, 376, an outer surface of the FPC 310 below a radially protruding circumferential rim 311 of the FPC 310. If the outer geometry of the FPC were redesigned to have a different shape (e.g., cuboid), then the shape and length of the fork arms 374, 376 may be re-designed accordingly (e.g., straight, or having a different FPC-mimicking curvature), if necessary to enable the fork lift end effector to couple with and support the FPC after FPC redesign. FIG. 31C depicts the forklift end effector 372 removing the FPC 310 from the open cubby 616. The view of FIG. 31C shows the fork arm 374

supporting the FPC 310 beneath the protruding circumferential rim 311 so that the FPC 310 does not fall.

FIG. 32 is a perspective view of a key lift end effector 872 of an internal transport system 864 of an autonomous food station 800, according to an alternative embodiment of the present invention. In the view of FIG. 32, the key lift end effector 872 is coupled to and supporting an FPC 810 in the common transport space in front of a cubby 616 and a plurality of similar cubbies. Now referring additionally to FIGS. 33A and 33B, an example configuration of the key lift end effector 872 is shown, which includes a proximal end 876 that couples to the internal transport system 864 by conventional means (e.g., fasteners not shown), and a distal end 874 that is configured to couple with and support a receiving handle 865 of the FPC 810. If the receiving handle 865 of the FPC 810 were redesigned to have a different shape or size, then the shape and size of the distal end 874 of the key lift end effector may be re-designed accordingly (e.g., to fit the redesigned receiving handle) to enable the key lift end effector to couple with and support the FPC after receiving handle redesign.

FIG. 33B depicts the key lift end effector 872 (separate from the rest of the internal transport system, for simplicity) approaching the FPC 810 within the cubby 616. As shown in FIG. 33B, the door actuation mechanism 650 had previously opened the front panel door 657 of the cubby 616. In certain preferred embodiments, the key lift end effector 872 is initially moved forward (e.g., by the internal transport system 864 shown in FIG. 32) at a vertical level that is below the receiving handle 865 of the FPC 810. The key lift end effector 872 may then be raised (e.g., by the internal transport system 864 shown in FIG. 32) to engage, couple with, and then lift the receiving handle 865 of the FPC 810 (and thereby lift and support the FPC 810 itself), so that the FPC 810 can thereafter be removed from the cubby 616, and internally transported within the autonomous food station 800.

If the FPC 810 is to be replaced within the cubby 616, the key lift end effector 872 would be lowered (by the internal transport system 864) sufficiently beyond the level at which the bottom of the FPC 810 rests upon the floor of the cubby 616, thereby disengaging the key lift end effector 872 from the receiving handle 865 of the FPC 810. The key lift end effector 872 could then be removed from the cubby 616, without the FPC 810, leaving the FPC 810 within the cubby 616, after which the door actuation mechanism 650 could close the front panel door 657 of the cubby 616, for example to maintain a temperature difference between the interior of the cubby 616 and other spaces within the autonomous food station 800.

FIG. 34A is a perspective view of a tray end effector 880 approaching an FPC 808 in a cubby 820, according to an alternative embodiment of the present invention. In the example embodiment of FIG. 34A, the tray end effector 880 includes a FPC support tray 801, an internal transport system coupling feature 883, and a hook 804. In the embodiment of FIG. 34A, the tray end effector 880 also includes a conventional linear actuator 802 that can pull the hook 804 forwards or backwards relative to the FPC support tray 801. The tray end effector 880 may be coupled to an internal transport system (e.g., the internal transport system 864 of FIG. 32) by conventional fasteners, for example, by connection to the tray 801 or to the coupling feature 883 (conventional fasteners not shown).

In FIG. 34A, the tray end effector 880 is approaching the FPC 808 at a level in which the hook 804 is above an example receiving handle 806 of the FPC 808. FIG. 34B is

a perspective view of the tray end effector 880 after having been lowered (e.g., by the internal transport system 864 of FIG. 32) to engage the hook 804 with the receiving handle 806 of the FPC 808, thereby coupling the tray end effector 880 with the FPC 808. FIG. 34C is a perspective view of the tray end effector 880 after the FPC 808 has been pulled on to the FPC support tray 801 by the conventional linear actuator 802 pulling on the hook 804. After internal transport of the FPC 808 within the autonomous food station to a desired destination (e.g., an oven, another cubby, or a collection hatch), the conventional linear actuator 802 can push on the hook 804 to slide the FPC 808 off of the support tray 801, and then the internal transport system can lift the tray end effector 880 to disengage the hook from the receiving handle 806 of the FPC 808, thus decoupling the tray end effector 880 from the FPC 808.

FIG. 35 is a perspective view of a conveyor belt end effector 972 of an internal transport system 964 of an autonomous food station 900, according to an alternative example embodiment of the present invention. FIGS. 36A and 36B depict different perspective views of the example conveyor belt end effector 972 (separate from the rest of the internal transport system, for simplicity). FIG. 36C depicts an optional configuration for a mechanism 940 to drive the conveyor belt 974 of the end effector 972.

In the example embodiment of FIGS. 35, 36A, 36B, and 36C, the conveyor belt end effector 972 includes a conveyor belt 974 and a support frame 976 that can be coupled to the internal transport system 964, for example by conventional fasteners. In certain embodiments, the conveyor belt 974 may be driven by a roller 943 that is coupled by gears 941 and 942 to a servo-controlled or stepper motor 945, however other conventional methods to drive the conveyor belt 974 are contemplated herein.

FIG. 37A depicts a cubby 916 of an autonomous food station according to an example embodiment of the present invention that utilizes the conveyor belt end effector 972, shown with its front panel door 957 actuated to a closed position by a door actuation mechanism 650 that may optionally include a rack 652 and a pinion gear 651. FIG. 37B depicts the cubby 916, except with its front panel door 957 actuated to an open position by the door actuation mechanism 650. In the example embodiment of FIGS. 37A and 37B, the cubby 916 includes a recess 912 in its FPC support floor 913, and the front panel door 957 of the cubby 916 includes a corresponding downward protrusion 958 to cover the recess 912 (e.g., to more efficiently maintain a temperature difference between the interior of cubby 916 and its outside environment).

In certain embodiments, such as the embodiment of FIGS. 37A and 37B, the recess 912 allows the conveyor belt end effector 972 to enter the interior of the cubby 916 beneath the bottom of a FPC within the cubby 916, so that FPC can be subsequently lifted to rest upon the conveyor belt 974 (e.g., by action of the internal transport system 964 of FIG. 35). However, in certain alternative embodiments the function of the recess 912 may be replaced by a FPC support frame within the cubby, or by raised floor ledges within a taller or larger cubby, such that the cubby doors can remain rectangular (e.g., as shown in the autonomous food station 900 of FIG. 35). FIG. 38A depicts the conveyor belt end effector 972 approaching a FPC 710 inside the open cubby 916 (of the example embodiment of FIG. 37B).

Now referring to FIGS. 35-38A, in the example embodiment of FIG. 38A, the internal transport system 964 may align the conveyor belt end effector 972 with the recess 912 as the conveyor belt end effector 972 approaches the interior

of the cubby 916. FIG. 38B depicts the conveyor belt end effector 972 after it is partially inserted into the recess 912 of cubby 916, in position beneath the FPC 710. FIG. 38C depicts the conveyor belt end effector 972 retrieving the FPC 710 from the cubby 916. In certain embodiments, the internal transport system 964 need not lower or lift the conveyor belt end effector 972 before, as, or after it is horizontally partially inserted into the recess 912 below the FPC 710, to retrieve the FPC 710.

For example, in such embodiments the conveyor belt end effector 972 may be inserted horizontally at a constant height where the conveyor belt 974 is already slightly higher than the floor 913 of the cubby 916, while the conveyor belt 974 is driven horizontally rearward (e.g., at the same rate that the conveyor belt end effector 972 is inserted horizontally into the recess 912). In that case, the rearward driving of the conveyor belt 974 lifts the FPC 710 on to the conveyor belt 974 (already in a vertical position higher than the floor 913 of the cubby 916), e.g., without sliding therebetween. In such embodiments, the internal transport system 964 need not lower the conveyor belt end effector 972 to clear the FPC 710 on insertion, nor raise the conveyor belt end effector 972 to lift the FPC 710 to retrieve it after insertion.

FIG. 39 is a perspective view of the internal transport system 964 moving a FPC 710 in the common transport space within the autonomous food station 900, the FPC 710 supported by the conveyor belt end effector 972. In this embodiment, the conveyor belt 974 would generally not be driven during internal transport of the FPC 710 within the common transport space of the autonomous food station 900.

In the foregoing specification, the certain components of the inventive autonomous food station may be described, specified, or claimed with reference to a utility to act upon a food portion container, but the food portion container is not itself included nor claimed as a component of the autonomous food station. For example, certain components of the autonomous food station may be designed or sized to accommodate, move, or change the temperature of a food portion container, and may be specified in part with reference to that utility, but the food portion container is not part of the autonomous food station. The distinction may be illustrated by analogy to a writing pen. The pen is designed and sized to enable a hand to write on paper. Although the hand and paper are necessary for the intended and specified utility of the pen, and the characteristics of the hand and paper affect and motivate the design of the pen, neither the hand nor the paper is properly considered to be part of the pen.

In the foregoing specification, the invention is described with reference to specific exemplary embodiments, but those skilled in the art will recognize that the invention is not limited to those. For example, the word "preferably" is used herein to consistently include the meaning of "not necessarily" or optionally. "Comprising," "including," and "having," are intended to be open-ended terms. It is also contemplated that various features and aspects of the invention may be used individually or jointly and possibly in a different environment or application, and various changes in form and detail may be made without departing from the spirit and scope of the invention. The specification and drawings are, accordingly, to be regarded as illustrative and exemplary rather than restrictive, and the invention should be limited only according to the following claims, including all equivalent interpretation to which they are entitled.

We claim:

1. A food station comprising:
a plurality of cubbies, each cubby sized to enclose a food portion container in a cubby interior space, each cubby including a cubby door and a door actuation mechanism that can open and close the cubby door independently from that of other cubbies,

a heating system that can controllably heat the food portion container within at least a first one of the plurality of cubbies;

a cooling system that can perform cooling within at least a second one of the plurality of cubbies;

an internal transport system including an end effector that temporarily couples to the food portion container and controllably moves the food portion container in a common transport space within the food station; and a control system that controls the heating, controls the opening and closing of the cubby door of each of the plurality of cubbies, and controls the movement of the internal transport system, the control system including a memory that stores information used by the control system;

wherein the cubby door, when closed, closes off the corresponding cubby interior space sufficiently to enable the control system to control a temperature within that cubby to be substantially different from that of the common transport space within the food station.

2. The food station of claim 1 wherein the cooling system can also perform cooling within the first one of the plurality of cubbies.

3. The food station of claim 1 wherein the heating system can also perform heating within the second one of the plurality of cubbies.

4. The food station of claim 1 wherein the heating system performs heating within the first one of the plurality of cubbies independently from heating within others of the plurality of cubbies.

5. The food station of claim 1 further comprising a collection hatch that has an external shutter that can be actuated by the control system to selectively control the external accessibility of the collection hatch.

6. The food station of claim 5 wherein the collection hatch includes an internal shutter that can be actuated by the control system to selectively deny access from the collection hatch to the common transport space within the food station while the external shutter is open.

7. The food station of claim 1 further comprising a label scanner, and the stored information includes information read by the label scanner from a label on the food portion container.

8. The food station of claim 7 wherein the internal transport system controllably moves the food portion container carrier through the common transport space within the food station to an internal identification site that includes the label scanner.

9. The food station of claim 1 further comprising communication electronics capable of receiving information via the internet, and the stored information includes information received via the internet.

10. The food station of claim 1 wherein internal transport system includes controllable mechanical actuators that translate the end effector in three orthogonal directions, each forming an axis of a Cartesian coordinate system.

11. The food station of claim 1 wherein the end effector comprises two support arms that are sized and spaced to partially envelop, between the two support arms, an outer surface of the food portion container.

25

12. The food station of claim **11** wherein the end effector further comprises an actuation mechanism to enable the control system to actuate the two support arms relative to each other to radially clamp on the outer surface of the food portion container.

13. The food station of claim **1** wherein the end effector comprises a distal key that is sized and shaped to engage and couple with a handle of the food portion container and thereby support the food portion container.

14. The food station of claim **1** wherein the end effector comprises a support tray, a hook, and a linear actuator attached to the hook, and the hook is sized to engage with a handle of the food portion container so that the linear actuator can pull the food portion container on to the support tray.

15. The food station of claim **1** wherein the end effector comprises a conveyor belt and a conveyor belt driving mechanism that is controlled by the control system.

16. The food station of claim **15** wherein a floor of the selected cubby includes a recess sized to accept partial

26

insertion by the conveyor belt of the end effector, and the cubby door, when closed, covers the front of the recess.

17. The food station of claim **16** wherein the cubby door includes a downward projection to cover the front of the recess.

18. The food station of claim **1** wherein the door actuation mechanism includes a motor and a pinion gear driven by the motor, and the cubby door includes a rack gear engaged with the pinion gear.

19. The food station of claim **18** wherein the door actuation mechanism and the rack gear are disposed outside of the cubby interior space.

20. The food station of claim **1** wherein the plurality of cubbies are arranged in a rectilinear array, and the cubby door is configured as a sliding door that slides along a plane that is canted with respect the rectilinear array sufficiently for the sliding door to clear the adjacent cubby when opened.
